(57) **CLAIM**

The ornamental design for an itch scratcher, as shown and described.

DESCRIPTION

FIG. 1 is a perspective view of an itch scratcher showing my new design;

FIG. 2 is another perspective view thereof;

FIG. 3 is a front elevation view thereof;

FIG. 4 is a back elevation view thereof;

FIG. 5 is a left side view thereof;

FIG. 6 is a right side view thereof;

FIG. 7 is a an enlarged top plan view thereof;

FIG. 8 is an enlarged bottom plan view thereof; and,

FIG. 9 is an enlarged view of portion "9" shown in FIG. 4.

The broken lines illustrate enlarged view indicators and form no part of the claimed design.
